Des. 199,661
Patented Dec. 1, 1964

199,661

DRINKING STRAW

Leonard B. Rosen, R.D. 2, Jamestown, Pa.

Filed Feb. 17, 1964, Ser. No. 78,651

Term of patent 14 years

(Cl. D2—3)

FIG. 1

FIG. 2

FIG. 3

FIG. 6

FIG. 4

FIG. 5

FIGURE 1 is a plan view of a drinking straw embodying my new design;

FIGURE 2 is a plan view of a modified drinking straw embodying my new design;

FIGURE 3 is a plan view of the straw shown in FIGURE 1 but with the upper portions of the straw separated;

FIGURE 4 is an end view of the bottom of the straw shown in FIGURE 1;

FIGURE 5 is an end view of the bottom of the straw shown in FIGURE 2; and

FIGURE 6 is a plan view of the straw shown in FIGURE 2 but with the upper portions of the straw separated.

The undisclosed sides of the straws of FIGURES 1 and 2 are substantially the same in appearance as the sides shown in said figures.

I claim:

The ornamental design for a drinking straw, as shown and described.
